US0D1065788S

(12) United States Design Patent (10) Patent No.: US D1,065,788 S
(45) Date of Patent: * Mar. 11, 2025

(54) FOOTWEAR

(71) Applicant: Crocs, Inc., Broomfield, CO (US)

(72) Inventor: Melissa Gallagher, Louisville, CO (US)

(73) Assignee: Crocs, Inc., Broomfield, CO (US)

() Term: 15 Years

(21) Appl. No.: 29/872,056

(22) Filed: Mar. 6, 2023

(51) LOC (15) Cl. 02-04

(52) U.S. Cl.

USPC D2/916

(58) Field of Classification Search

USPC D2/896–900, 903, 904, 909, 910, 913, D2/916–924, 925–945, 947–960, 969–978

(57) CLAIM

The ornamental design for footwear as shown and described.

DESCRIPTION

FIG. 1 is a top perspective view of footwear;

FIG. 2 is a front view thereof;

FIG. 3 is a back view thereof;

FIG. 4 is an outer side view thereof;

FIG. 5 is an inner side view thereof;

FIG. 6 is a top view thereof; and,

FIG. 7 is a bottom view thereof.

The elements shown in FIGS. 1–7 that are overlaid with a white transparent mask bounded by broken lines represent portions that form no part of the claimed design.

1 Claim, 7 Drawing Sheets
